(57) **CLAIM**

The ornamental design for a multifunctional handheld fan, as shown and described.

DESCRIPTION

FIG. 1 is a front, right and top perspective view of a multifunctional handheld fan, showing my new design.

FIG. 2 is a rear, left and top perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is rear, right and top perspective view of the multifunctional handheld fan of FIG. 2, shown in a position of use; and,

FIG. 10 is another rear, right and top perspective view of the multifunctional handheld fan of FIG. 2, shown in a position of use.

The broken lines shown in the drawings illustrate portions of the multifunctional handheld fan that form no part of the claimed design.
